UNITED STATES PATENT OFFICE.

HENRY F. BECHMAN, OF BATTLE CREEK, MICHIGAN, ASSIGNOR TO DUPLEX PRINTING PRESS COMPANY, OF BATTLE CREEK, MICHIGAN, A CORPORATION OF MICHIGAN

ROTARY WEB-PRESS.

No. 854,142.

Specification of Letters Patent.

Patented May 21, 1907.

Application filed September 1, 1906. Serial No. 333,013.

To all whom it may concern:

Be it known that I, HENRY F. BECHMAN, of Battle Creek, in the county of Calhoun and State of Michigan, have invented certain new 5 and useful Improvements in Rotary Web-Presses; and I hereby declare that the following is a full, clear, and exact description thereof, reference being had to the accompanying drawings, which form part of this 10 specification.

This invention is an improvement in rotary web-printing presses, and its object is to provide a press of large capacity, and in which the webs will run straight from the 15 rolls through the printing mechanisms to the folders and can be assembled thereat, the webs entering at one side of the press and passing to the folders at the opposite side of the press without any lateral deflection or 20 bends in the web and without any turners or angle bars being required between the web rolls and the folder formers.

The invention is an improvement upon the press shown in my Patent No. 814,510 dated 25 March 6, 1906, and contains a number of sections, four being shown in the drawing, each section containing two plate and two impression cylinders. The plate cylinders, as shown, can carry eight plates. On straight 30 run non-collecting printing the plates on opposite sides of each cylinder are duplicates, so that in such case each section would print eight pages for each half rotation of the cylinder and no collecting of the sheets will be 35 necessary and the product of each section would be eight pages.

The product of each section can be folded separately if desired so that in this arrangement the press could produce four eight page 40 papers simultaneously; or by assembling the products of two or more sections I can produce papers in multiples of eight pages up to thirty-two pages. If desired, the size of the 45 papers can be increased, although the speed of their production will be correspondingly reduced, by having each plate cylinder carry eight separate and distinct page plates. This arrangement necessitates "collecting" the sheets at the folder and in such case the product 50 of each section would be sixteen pages collected, and of the complete press any multiple of sixteen pages up to sixty-four pages. In this case the webs may be assembled before cutting, and collected after cutting, for the

pages printed by the set of plates on one side 55 of each cylinder must be assembled side by side with the pages printed by the other sets of plates on the cylinders. Either arrangement of the plates, and the assembling and collecting of the webs and papers will be instantaneously understood by pressmen, and needs no detailed explanation herein. Of course the double size papers produced by the collecting process are produced only one-half as rapidly as the single-size-papers, although at 60 each operation of the machine the same number of pages can be printed.

Obviously any section of the press can be used to print less than eight pages, or any multiple of two pages up to eight without collecting, by using a proper narrow width web, and I can use one or more sections printing full-width webs in combination with another section or sections printing narrow width web or webs, and assemble these webs at the 70 folder or folders, to produce papers of an unusual number of pages, as fourteen, eighteen, twenty-two, etc. I can also in this machine simultaneously produce a number of papers of the same or different sizes, as for examples, 75 I can simultaneously produce four eight page papers; or two twelve page papers; or one twelve and one sixteen page papers; or one thirty-two page paper or twenty page paper; in fact papers of any desired size up to the 80 limit of the press can be produced.

The press is so constructed that it has two rows of perfecting mechanisms arranged in parallel, and each row may contain two or more sets of perfecting mechanisms which 85 are arranged end to end and closely adjacent, and preferably all the plate cylinders are in the same horizontal plane, and access can be had to all the cylinders from the floor, and in fact every part of the press can be 90 reached from the floor, so that the pressman in making ready the press, or in adjusting the parts, does not have to climb into or over any portions of the machine,—as is necessary in the heretofore known large rotary presses, 95 and by reason of this low-down arrangement the press can be erected in a basement or in low-ceilinged rooms, and does not require a special construction of press-room. It contains all the advantages of my said patented 100 rotary press while practically greatly enlarging the capacity and flexibility of such machine.

I will now describe the press with reference to the accompanying drawings, in which:

Figure 1 is a top plan view of the complete machine; Fig. 2 is a side elevation thereof; Fig. 3 is a transverse section of the press on line 2—2, Fig. 1. Figs. 4, 5, 6, 7 and 8 are diagrammatical views illustrating how papers of different sizes can be produced on the machine.

The press as shown has four sets of perfecting mechanisms A, B, C, D, each comprising two plate cylinders 1, 1^a and co-acting impression cylinders 2, 2^a. These mechanisms are arranged in two rows at opposite sides of the press, the cylinders in the adjacent mechanisms being arranged longitudinally of the press, the adjacent sets of cylinders being end to end, and all the cylinders being in substantially the same horizontal plane and lying close to the floor, so that all the outermost cylinders 1^a 1^a can be easily reached by the pressman from the outer sides of the press; and the inner cylinders 1, 1, of the adjacent rows are sufficiently separated to leave an alley-way so that the pressman can easily walk between the two rows to put the plates on and off the inner cylinders while standing on the floor.

Each cylinder is provided with a related set of inking mechanism 3, 3^a, which is constructed preferably as described in my Patent No. 823,098, of June 12, 1906, and needs no particular description herein, the inking mechanism, however, being also extended longitudinally of the press and being conveniently accessible from the outer sides and alley-way thereof at all times.

The cylinders in each set are intergeared as indicated in the drawings, so that they can be rotated synchronously and may be driven by trains of gears 4^a from gears 4^b on the main driving shaft 4. Each section may be directly geared to the main shaft 4, as indicated in Fig. 2, and by making one of the gears in each train of gears 4^a removable, or shiftable on its shaft into or out of mesh with the others, any of the perfecting mechanisms can be put in or out of operation at the will of the operator.

As shown in Figs. 1 and 3, a web w' may be led in from roll W' under and over guides 5, 5^a through the perfecting mechanism A, then up over guide 5^b, across the machine to and under a guide 5^d, being slit at or before reaching this guide by a slitter as at S', then the adjacent halves of the webs may pass directly to and over the formers F', F², located beside the perfecting mechanism B at the side of the press opposite the roll W', and each half of the web w' may, if desired, be folded separately, in which case,—when printing in the straight non-collecting method,—the product of the web W' will be two 4 page papers. Similarly the web w² may be

led from a roll W² under and over guides 6^a, 6^b to and through the perfecting mechanism B, (which is at the side of the press opposite mechanism A, but parallel with the latter,) and then passed over guides 6^c and 6^d, down and around guide 6^e, and up and over guide 6^f, to the formers F', F², the web w² being first slit at a convenient point after being printed, as by means of the slitter S² located adjacent the roller 6^e, the two webs w', w² being assembled on the formers F', F² and thus—with the straight-line non-collecting method, 8 page papers will be delivered at each folder. Similarly a web w³ may be led in from roll W³ to and through the printing mechanism C, which is in axial alinement with the mechanism A, and passed over guides similar to those used for web w' to folder formers F³, F⁴, at the same side of the press as formers F' and F², but beside the printing mechanism D. While another web w⁴ may be led from roll W⁴ in a manner similar to web w³, to and through the perfecting mechanism D, and assembled with web w³ on the formers F³, F⁴.

Each former is provided with the usual first fold rolls (f', f², f³, f⁴ respectively), at its apex; and adjacent each former is a web-folding mechanism G', G², G³, G⁴ which may be of the usual construction, and adjacent each folding mechanism is a collector H', H², H³, H⁴, also of ordinary construction, therefore said folding and collecting devices are simply diagrammatically indicated in the drawings as their construction and mode of operation are well understood.

Adjacent the apex of former F' may be placed a web guide g'; and at the apex of formers F², F³ may be placed web guides g², g³, and at the apex of former F⁴ may be placed a web guide g⁴; these guides being used in assembling the webs as hereinafter explained.

If each plate cylinder carries two sets of 4 single-page plates, the product of each section will be 8 pages, and with the webs running to the formers, as above described (that is one-half of each web w', w² to former F' and the other half w', w² to former F²; and half of each web w³, w⁴ to former F³, and the other halves of webs w³ and w⁴ to former F⁴, as indicated in Fig. 4), the product of the machine will be four 8 page papers delivered from folders G', G², G³, G⁴ without collecting.

If desired, the two halves of webs w', w² can be assembled after passing the formers F', F² by leading one-half of the webs, say those passing over former F², from the first fold rolls f² under guide g² to and over guide g' and down into folder G'; and the two halves of the webs w³ and w⁴ can be brought together in the folder G³ as indicated in Fig. 5 of the drawings. In this manner two 16 page papers can be delivered simultaneously from the machine on a straight non-collect-

ing run. Again if desired, all the webs delivered from the several formers can be assembled at one folder G^2 , as indicated in Fig. 2 of the drawing, which with the non-collecting method, would produce a 32 page paper.

If the collecting system is employed, that is each plate cylinder having 8 separate page-plates, the size of the papers produced will be doubled, but the speed will be reduced one-half,—and with this method, if the webs are assembled as shown in Fig. 4, 16-page papers could be produced using collectors H' , H^2 , H^3 , H^4 , and as shown in Fig. 5 two 32 page papers could be produced by using the collectors H' , H^3 ; and by assembling the webs, as shown in Fig. 2 and using collector H^2 one 64-page paper could be produced.

By using a narrow width web in some of the perfecting mechanisms, and full width webs in others, papers of any desired number of pages can be produced. Thus three-quarter-width webs could be used in mechanisms C, D, and a half-width web in mechanisms A, B, which will produce a twenty page paper without collecting, or by collecting produce a 40 page paper; but in producing papers of such size when it is not desired to run the entire press, a full width web could be printed in sections A, B, to produce 16 pages, and a four page web could be printed in section D or C. Again, two 12 page papers non-collecting (or 24 pages collecting) could be produced by running full-width webs in sections C, D, and half-width webs in sections A, B, and again dividing the halves of the full width webs printed on sections C, D, before passing over former F^3 and directing three-quarters of such webs to the folder G^4 ; and lead the other quarters of these webs to the folder G^2 and assembling it there with the half width webs printed on mechanisms A, B. Again, two different sized papers can be produced simultaneously; for example, full width webs could be printed on mechanisms C, D, and three-quarter width webs on mechanisms A, B; the halves of webs could be again split before passing over former F^3 , and three-fourths of the webs could be assembled and folded at G^4 , while the other fourth of such webs could be led over to folder G^2 and assembled thereat with the three-quarter width webs printed on mechanisms A, B, and of course, in the examples illustrated in Figs. 7 and 8, if the collecting method was employed, the size of the paper produced would be doubled.

The foregoing will impart a clear idea of the flexibility of the press, and the large variety of papers which can be produced thereon, and it will be observed that it can be operated at very high speed because the papers are not turned or deflected from their path until they have passed the formers, and by providing as many formers as there are perfecting mechanisms, I am able to take

care of the product of all the mechanisms at any desired speed, and by having the folding mechanisms all adjacent and in line, the webs can be directed into any one or more of them.

70

By this construction of press a low-down simple high speed press of great capacity and variety of product is produced; and the capacity of such press can be increased readily by increasing the number of perfecting mechanisms in the rows, or by superposing another tier of such mechanisms above the ground tier.

75

Having described my invention what I claim as new and desire to secure by Letters Patent is:

1. In a rotary printing press, the combination of two parallel series of rotary perfecting mechanisms arranged in substantially the same plane, each series containing two rotary perfecting mechanisms end to end, the cylinders in each mechanism extending longitudinally of the press, and all the cylinders being in substantially the same plane; with a corresponding number of formers at one side of the press, folding mechanisms adjacent the formers, guides for directing webs through each perfecting mechanism straight to the formers without lateral deflection of the webs, and means whereby the webs can be directed into the same or any separate folding mechanism.

2. In a rotary printing press, the combination of parallel series of rotary perfecting mechanisms arranged in substantially the same plane each series comprising a plurality of rotary perfecting mechanisms arranged end to end, the cylinders in each mechanism extending longitudinally of the press; with a corresponding number of formers at one side of the press, a folding mechanism, adjacent each former guides for directing webs through each perfecting mechanism straight to the formers without lateral deflection of the webs, means for slitting the webs, and means whereby the sections of the webs can be directed into any folder.

3. The herein described rotary press, comprising two parallel series of perfecting mechanisms arranged in substantially the same plane each series comprising a plurality of perfecting mechanisms arranged end to end longitudinally of the press, the cylinders in the several mechanisms being in substantially the same horizontal plane, a corresponding number of formers at one side of the press, means for directing the webs printed on the perfecting mechanisms into the adjacent formers without lateral deflection of the webs, means for slitting the webs before reaching the formers, a folding mechanism beside each former, guides for directing the webs through the press, and means whereby the webs may be directed from any former into any folder.

4. The herein described rotary press, com-

125

130

prising two parallel series of perfecting mechanisms, each series comprising two perfecting mechanisms arranged end to end longitudinally of the press, the cylinders in the several mechanisms being in substantially the same horizontal plane, a former for each mechanism at one side of the press, means for directing the webs printed on transversely adjacent perfecting mechanisms into the relative adjacent formers without lateral deflection of the webs, means for slitting the webs before reaching the formers, a folding mechanism beside each former, guides for directing the webs through the press, and means whereby the webs or sections thereof may be directed from any former into any folder.

5. In a rotary printing press, the combination of parallel series of rotary perfecting mechanisms, each series comprising a plurality of rotary perfecting mechanisms, the cylinders in each mechanism extending longitudinally of the press; with a corresponding number of formers at one side of the press, a folding mechanism, adjacent each former guides for directing webs through each perfecting mechanism straight to the formers without lateral deflection of the webs, means for slitting the webs, and means whereby the sections of the webs can be directed into any

folder; with a collector adjacent each folding mechanism, and means for driving the several perfecting mechanisms in unison.

6. In a rotary printing press, the combination of two parallel series of rotary perfecting mechanisms in substantially the same plane, each series comprising two rotary perfecting mechanisms, the cylinders in each mechanism extending longitudinally of the press, and all the cylinders being in substantially the same plane; with a corresponding number of formers at one side of the press, a folding mechanism adjacent each former, guides for directing webs through each perfecting mechanism straight to the formers without lateral deflection of the webs; means for operating the perfecting mechanisms in unison, and means whereby one or more of the perfecting mechanisms may be put out of operation; with a collector adjacent to each folding mechanism, and means for driving the several perfecting mechanisms in unison.

7. In testimony that I claim the foregoing as my own, I affix my signature in presence of two witnesses.

HENRY F. BECHMAN.

Witnesses:

CHARLES A. GRAMES,
F. W. DUNNING.
